US0D1017158S

(12) **United States Design Patent** (10) **Patent No.:** **US D1,017,158 S**
(45) **Date of Patent:** **** Mar. 5, 2024**

(54) **WATER TANK FOR CLOTHES MANAGEMENT APPARATUS**

(71) Applicant: **LG ELECTRONICS INC.**, Seoul (KR)

(72) Inventors: **Donghwan Lee**, Seoul (KR); **Hoil Jeon**, Seoul (KR); **Kyungah Lee**, Seoul (KR); **Kihyuk Kim**, Seoul (KR)

(73) Assignee: **LG ELECTRONICS INC.**, Seoul (KR)

(**) Term: **15 Years**

(21) Appl. No.: **29/816,263**

(22) Filed: **Nov. 19, 2021**

(30) **Foreign Application Priority Data**

May 21, 2021 (KR) 30-2021-0024216

(51) **LOC (14) Cl.** **15-05**

(52) **U.S. Cl.**

USPC **D32/25**

(57) **CLAIM**

The ornamental design for a water tank for clothes management apparatus, as shown and described.

DESCRIPTION

FIG. 1 is a front perspective view of the water tank for clothes management apparatus showing our new design; FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is a reference view showing the state of use that the cap at the top part has been opened;

FIG. 10 is a reference view showing the state of use that the top cover is being separated by pressing the left and right buttons; and,

FIG. 11 is a reference view showing the state of use that the claimed design has been installed in a clothes management apparatus.

The broken lines depict portions of the water tank for clothes management apparatus that form no part of the claimed design. The portions of FIG. 11 drawn in broken lines show environmental structure only and form no part of the claimed design.

1 Claim, 11 Drawing Sheets
